STOP MOTION

Jesse L. Bridges and Hillary L. Sullivan, Riverview, Ala.

Application September 20, 1952, Serial No. 310,692

8 Claims. (Cl. 57—79)

This invention relates to roving machines, slubbers, and the like for drawing and winding yarn and, more especially, this invention relates to an improved stop-motion therefor which cooperates with the conventional stop-motion of a roving machine or the like to accurately control the stopping of the machine to insure that the usual presser feet carried by the flyers of such machines are always stopped at a predetermined doffing position relative to the bobbins on which the yarn is wound preparatory to the usual doffing operation.

Hereinafter, the invention will be described in association with a roving machine, however, it is to be understood that the present invention may be used in association with analogous machines such as slubbers, speeders, and the like.

As is well known to those familiar with the art, roving frames and the like are provided with cone pulleys, one of which drives the other and the other of which causes variations in the speed of the spindles according to the diameter of the yarn wound on the bobbins carried by said spindles. The cone pulleys are engaged by a belt which is shifted by means of a cone-rack. This cone-rack moves longitudinally of the machine and, upon the bobbins being substantially filled with yarn, a projection or bunter on the rack engages and raises a latch arm of a conventional stop motion out of engagement with a retaining means therefor which permits the usual knock-off lever or swing lever which controls the shipper rod to move to inoperative position, thereby moving the shipper rod, by means of which the usual driving belt of the machine is passed from the fast pulley to the loose pulley to stop the machine.

The mechanism for stopping the machine as above described has not been entirely satisfactory due to the fact that the usual flyers having presser feet thereon which direct the yarn or roving to the bobbins, will stop in various positions relative to the bobbins each time the machine is stopped automatically and it would be necessary for the operator to move the conventional shipper rod several times into operative position and then return the same to inoperative position in order to insure that the presser foot associated with each of the bobbins would be located in a "doffing" position about midway of the corresponding bobbin. Since most operators of these machines are paid on a piece-work basis, they often fail to manipulate the shipper rod, as above stated, with the result that, when the flyers stop in positions other than the optimum doffing position, the yarn or roving becomes entangled during the doffing operation and, in many instances, a substantial number of turns of the roving or yarn are unwound from the bobbins resulting in considerable waste.

It is the primary object of this invention to overcome such defects as above described by providing an improved stop-motion, for roving machines and the like, which operates in conjunction with the usual stop-motion of the machine to insure that the presser feet carried by the flyers of the machine stop at a given position relative to the corresponding bobbins each time the bobbins have been filled with roving or yarn to thereby facilitate an efficient doffing operation.

Roving machines and the like have a rock-shaft which oscillates in timed relation to the operation of the usual builder motion and, more specifically, it is an object of this invention to provide an auxiliary stop-motion which operates in conjunction with the usual stop-motion of the

2

roving machine and which improved stop-motion comprises an auxiliary latch which normally engages said conventional latch arm connected to the swing lever. A unique cam arrangement fixed on the rock-shaft raises or moves said auxiliary latch out of engagement with the conventional latch arm upon movement of the rock-shaft in one direction, but fails to move the auxiliary latch upon movement of the rock-shaft in the opposite direction.

10 However, the auxiliary latch is ineffective in releasing the conventional latch arm connected to said swing lever until said projection or bunter on the cone-rack has engaged and raised the conventional latch arm out of engagement with its restraining means, as heretofore described. Heretofore, the raising of the conventional latch arm out of engagement with its restraining means have caused the machine to stop substantially simultaneously therewith. However, the flyers might not be in the proper position for the doffing operation and, since 15 the rock-shaft moves in unison with the longitudinal movement of the flyers relative to the bobbins, the cam means on the rock-shaft will engage suitable connections to raise the auxiliary latch out of engagement with a notch in the conventional latch arm and will thereby 20 release the conventional latch arm after it has first been released from the normal restraining means.

This insures that the machine will not stop every time the auxiliary latch is raised out of engagement with the notch in the conventional latch-arm. On the other hand, 25 the auxiliary latch will restrain the conventional latch arm for a predetermined period after the conventional latch arm has been released from the conventional restraining means, i. e. until the presser feet on the flyers have moved in a predetermined vertical direction and 30 to a predetermined position relative to the bobbins following the releasing of the latch arm from the conventional restraining means.

Some of the objects of the invention having been stated, 35 other objects will appear as the description proceeds, when taken in connection with the accompanying drawings, in which—

Figure 1 is a fragmentary and somewhat schematic rear elevation of a portion of a roving machine, speeder, 40 slubber or the like, sufficient to illustrate the improved stop-motion and showing the stop-motion in running position;

Figure 2 is an enlarged transverse vertical sectional view, mostly in elevation, taken substantially along the line 2—2 in Figure 1 and also showing the vertically 45 movable bobbin bolster rail and the associated flyers for directing strands of roving or yarn to the bobbins in one position;

Figure 3 is a fragmentary view similar to the upper portion of Figure 2, but showing the flyers in doffing position;

Figure 4 is an enlarged fragmentary view similar to the right-hand central portion of Figure 1, but showing the swing lever and associated parts in inoperative position, which position they occupy when the machine is 50 stopped;

Figure 5 is an enlarged fragmentary vertical sectional view, mostly in elevation, taken substantially along the line 5—5 in Figure 4;

Figure 6 is an enlarged fragmentary vertical sectional view, mostly in elevation, taken substantially along the line 6—6 in Figure 3, showing the stop motions in normal running position;

Figure 7 is a view similar to Figure 6, but showing the auxiliary latch of the improved stop-motion raised out of engagement with the conventional latch arm of the machine while the latch arm is still in running position;

Figure 8 is an enlarged view of the cam, shown in the lower central portion of Figure 2, for controlling the improved stop-motion and also showing the cam in another position in broken or phantom lines.

Referring more specifically to the drawings, the numeral 10 indicates a portion of the framework of a roving machine, slubber, speeder or the like. The portion 55 of the framework 10 is usually termed as a roll beam

and is usually supported on a plurality of vertical frame members including Samsons 11, only one of which is shown in the drawings, and this particular Samson 11 is usually termed as the third Samson. It is well known to those familiar with the art that roving machines and the like also include a head end and a foot end. The head end and the foot end and those Samsons other than the third Samson are not shown, since the present invention is disposed adjacent the third Samson and a disclosure of the remaining frame members of the machine is deemed unnecessary.

Upper and lower cones or cone pulleys 12 and 13 are usual parts of a roving machine and are connected by an endless belt 14. A longitudinally traveling rack 15 is provided with a fork 16 which embraces the belt 14 so that, as the rack 15 is moved, the belt 14 is caused to travel longitudinally of the cones to vary the speed of the spindles in the usual manner. The spindles, only two of which are shown in Figure 2, are indicated at 20 and each has a conventional flyer 21 removably secured on the upper end thereof, one of the legs of which has a presser foot 22 connected thereto for directing yarn or roving Y from the usual drawing rolls, not shown, through the corresponding leg of the flyer 21 and the presser foot 22 to a corresponding bobbin or yarn holder 23 adapted to be mounted on a bolster 24.

As is well known, the bolsters 24 are driven to rotate at a slower speed than, but in the same direction as, the corresponding spindles 20 and said bolsters 24 with the bobbins 23 thereon are caused to move vertically relative to the spindles 20 by means of a conventional builder motion, not shown. The bolsters 24 are supported for rotation on a bolster or bobbin rail 25 carried by a vertically movable frame 26. The vertically movable frame 26 has conventional lifter-racks 27 (Figure 1) formed thereon, only one of which is shown in Figure 1 disposed closely adjacent the Samson 11.

Each of the lifter-racks 27 is engaged by a corresponding pinion or gear 30 fixed on a conventional rock-shaft or lifting shaft 31 journaled in the Samson 11 and being driven to oscillate in the usual manner. Means for driving the rock-shaft or lifting-shaft 31 are disclosed in such patents as those numbered 640,874 and 2,452,873. Also, complete details of a roving frame and the driving means therefor are disclosed in a catalogue of parts of Saco-Lowell Shons entitled "Model D Controlled Draft Roving Frames" and a disclosure of said driving means is deemed unnecessary.

Mounted to slide in one or more guides 33, secured to the frame of the machine, is a shivver rod 34. As is well known, the shivver rod 34 is connected at its end to a shivver lever (not shown) by means of which the usual driving belt is passed from the loose pulley to the fast pulley, and vice versa. A tappet or abutment 35 is fixed on the shivver rod 34 and is adapted to be engaged by the upper end of a swing lever or knock-off lever 36 fulcrumed upon a stud 37 carried by a bracket 40 suitably secured to the beam 10.

The swing lever 36 is usually formed in two parts adjustably secured together, the lower part having a lateral arm 41 on which a weight member 42 is adjustably secured. The weight member 42 is sufficient to force the shivver rod 34 longitudinally and to throw the usual driving belt (not shown) from the fast to the loose pulley.

One end of a conventional latch arm 43 is pivotally connected to the lower end of the swing lever 36, as at 44, and is thus caused to move in one direction by the weight member 42. The other or free end of the conventional latch arm 43 projects through an aperture 45a (Figure 5) in a stop plate or bracket 45 suitably secured to the Samson 11. The latch arm 43 has a notch 46 in its lower surface adjacent the free end thereof and, when the machine is in operation, the notch 46 engages the plate 45, as shown in Figures 6 and 7, to prevent the lever 36 from being operated by the weight member 42 and shifting the shivver rod 34 and, consequently, to effect an automatic stopping of the machine.

The cone-rack 15 has a tappet or abutment 47 adjustably secured thereon which engages the latch arm 43 when the cone-rack 15 reaches the end of its movement from left to right in Figure 4. When the tappet or abutment 47 engages the latch arm 43, it raises the notch 46 out of engagement with said plate 45, whereupon the swing lever 36 is enabled to shift the shivver

rod 34 to stop the machine. The parts heretofore described are the usual parts of a roving frame or the like, and it is with these parts that the invention is adapted to be associated.

As heretofore stated, the rock-shaft or lifting-shaft 31 moves in one direction, say, a clockwise direction in Figures 2, 3, and 8, as the bolster rail 25 and the bobbins 23 move upwardly relative to the machine frame and the spindles 20. Of course, as the rock-shaft or lifting shaft 31 moves in the opposite or counter-clockwise direction in Figures 2, 3, and 8, the bolster rail 25 and the bobbins 23 move downwardly relative to the spindles 20. As is well known, the amount that the rock-shaft 31 is rotated and the coincident length of stroke of the bolster rail 25 is varied, according to the amount of yarn or roving wound about each of the bobbins 23, by the usual builder motion (not shown).

Accordingly, it is practically impossible to position the tappet or abutment 47 on the cone-rack 15 so that it will engage and release the latch arm 43 at the same time preparatory to each doffing operation, that is, upon the bobbins 23 being filled with yarn or roving. In order to facilitate removal of the flyers 21 from the spindles 20 during the doffing operation, without entangling adjacent turns of roving on the bobbins 23 and to prevent the roving from becoming unravelled as the flyers 21 are removed from the spindles 20, it is preferable that the bobbins stop in the course of a downward stroke of the bolster rail 25 and in such a position that the presser feet 22 are disposed at a point slightly below midway of the length of each package of yarn or roving formed on the bobbins 23. This relativity in the positions of the presser feet 22 on the flyers 21 and the bobbins 23 shall hereinafter be termed as the optimum doffing position (Figure 3).

Now, in order to stop the bobbins at said optimum doffing position, upon the desired amount of yarn or roving Y being wound about the bobbins 23, there is provided an improved stop-motion which operates in conjunction with the conventional stop motion embodied in the latch 43, the abutment 47 on the cone-rack 15 and the swing lever 30. Broadly, the improved or auxiliary stop-motion comprises an auxiliary latch or a movable restraining means with cam controlled means, operating in timed relation to the vertical reciprocatory movement of the bolster rail 25 and the bobbins 23, to intermittently move said auxiliary latch out of engagement with an abutment or notch in the latch arm 43 of the conventional stop-motion so that, upon said conventional latch arm being released from its conventional restraining means, as embodied in the plate 45, the subsequent movement of the auxiliary latch out of engagement with the corresponding abutment or notch in the conventional latch arm will release said latch arm to stop the machine simultaneously with the relative position of the bobbins and the flyers being such that the presser feet on the flyers occupy the optimum doffing position.

The auxiliary stop-motion comprises a vertically movable auxiliary latch 50 which is preferably L-shaped and is supported on the upper end of a vertically disposed and vertically movable rod or shaft 51. In this instance, the auxiliary latch 50 is pivotally connected to the upper end of the vertical rod 51 by means of a pin 52 which may be positioned in any one of a plurality of apertures 53 in the upper end of the rod 51 for adjustment purposes.

The auxiliary latch 50 is also pivotally supported, as at 54, by the Samson 11. In this instance, the plate 45 is formed with bifurcations 56 between which one end of the latch 50 is positioned and pivotally supported. The conventional latch arm 43 is provided with a second notch 57 in the upper edge thereof which is adapted to be intermittently engaged by the free end of the auxiliary latch 50 when the notch 46 is in engagement with plate 45. Thus, the left-hand wall of the notch 57 (Figure 4) serves as an abutment on the conventional latch arm 43 for engaging the auxiliary latch 50.

It is evident that, when the auxiliary latch 50 is in engagement with the notch 57 in the conventional latch arm 43 and the conventional latch arm 43 is released from the plate 45, the auxiliary latch or movable restraining means 50 prevents the latch arm 43 from moving left to right, in which direction said conventional latch arm 43 is normally urged by the weight member 42. Thus, this will

delay the stopping of the machine until the bobbins 23 have reached the optimum doffing position relative to the presser feet 22, at which time the auxiliary latch or restraining means 50 moves out of engagement with the notch 57 to release the conventional latch arm 43 and stop the machine.

The rod 51 is mounted for vertical movement in a guide block 60 suitably secured to the Samson 11. The lower end of the rod 51 has a transverse follower plate or tappet 62 suitably secured thereto, which is intermittently engaged by an auxiliary cam element or tumbler 63 pivotally supported, as at 64, on an eccentric cam element 65 fixed on the rock-shaft or lifting shaft 31. The auxiliary cam element or tumbler 63 is in the form of a segment of a disk thus defining a curved outer surface 63a and converging angular surfaces 63b and 63c (Figure 8).

It will be noted that the angular surface 63c is substantially longer than the surface 63b and the tumbler or auxiliary cam element 63 is pivotally connected to the eccentric cam 65 in off-center relation relative to the normal center of gravity of the tumbler or auxiliary cam element 63. When the eccentric portion of the eccentric cam 65 is positioned to the left of the vertical plane axis of the shaft 31 substantially as shown in solid lines in Figure 8, the surface 63c of the tumbler or auxiliary cam element 63 engages an abutment or stop pin 66 projecting laterally from the face of the eccentric cam 65, against which the auxiliary cam element or tumbler 63 is mounted, so that the follower engaging or point 63d of the tumbler 63 will miss the follower plate 62 as it moves thereby in a clockwise direction in Figures 2 and 8, although the latch 50 may be in engagement with the second notch 57 in the conventional latch arm 43.

However, as the eccentric cam 65 moves the center of gravity of the tumbler 63 beyond the vertical plane of the rock-shaft or lifting shaft 31, the tumbler 63 falls about its pivot point, causing the surface 63b to move into engagement with a second stop pin or abutment 67 also projecting laterally from the face of the eccentric cam 65, as shown in Figure 3, and in phantom lines in Figure 8.

Now, the second stop pin 67 is so positioned relative to the pivot point of the tumbler 63 that the high point or cam follower engaging end 63d of the tumbler 63 will then extend substantially further from the axis of the shaft 31 than does the curved surface 63a of the tumbler 63 when the surface 63c of the tumbler 63 is in engagement with the stop pin 66.

Thus, upon each counter-clockwise movement of the eccentric cam 65 with the shaft 31, and during which the bobbins 23 and the bolster rail 25 are caused to move downwardly, the high point or end 63d of the tumbler 63 engages and elevates the cam follower plate 62 and the rod 51 to thereby move the latch 50 out of engagement with the notch 57 in the conventional latch arm 43.

Now, since the tumbler 63 causes the latch 50 to move out of engagement with the notch 57 at precisely the same time upon each downward movement of the bobbins 23 and the bolster rail 25, it is thus seen that we have provided means whereby the relative positions of the bobbins and the flyers will be the same each time that the machine is stopped regardless of the time at which the abutment or tappet 47 on the cone-rack 16 releases the conventional latch arm 43 from the plate 45.

In the drawings and specification, there has been set forth a preferred embodiment of the invention and although specific terms are employed, they are used in a generic and descriptive sense only and not for purposes of limitation, the scope of the invention being defined in the claims.

We claim:

1. An improved stop motion for roving machines, slubbers, speeders and the like, said machines each having a vertically reciprocable rail, driven yarn holders carried by said rail, flyers for directing yarn to each of said yarn holders, a stop motion, a driven cone-rack and means carried by the cone-rack for actuating said stop motion; the combination of means to restrain operation of said stop motion upon actuation thereof by said means carried by the cone-rack, and means operable automatically upon said yarn holders reaching a predetermined position in the course of reciprocatory movement thereof relative to the flyers for releasing said stop motion from the restraining means to enable said stop motion to be effective in stopping the machine.

2. In a roving machine, slubber, speeder or the like

having a reciprocatory frame for carrying bobbins; a stop motion and means for automatically actuating the stop motion to stop the machine upon the completion of a substantial number of revolutions by the bobbins; the combination therewith of a restraining means normally restraining operation of the stop motion upon actuation thereof, and means operable automatically upon said reciprocatory frame approaching a predetermined position relative to the machine, and following actuation of the stop motion, for releasing the stop motion from the restraining means to stop the machine.

3. In a roving machine, slubber, speeder or the like having a vertically reciprocable frame for carrying bobbins; a first stop motion and means for automatically

15 actuating the first stop motion to stop the machine upon the completion of a substantial number of revolutions by the bobbins; the combination of an auxiliary stop motion having means to restrain operation of the first stop motion upon initial actuation of the first stop motion, and means operable automatically upon said reciprocable 20 frame approaching a predetermined position relative to the machine and following actuation of the first stop motion for releasing the first stop motion from the restraining means of the auxiliary stop motion to, then, stop the machine.

4. In a strand processing machine such as a roving machine, slubber, speeder or the like having a vertically reciprocatory frame, rotary bobbins carried by said frame, a flyer associated with each of said bobbins for directing

30 strand material to the bobbins, a stop motion, said stop motion including a latch arm normally biased in one direction, normal restraining means engaging said latch arm, and means on the machine for automatically releasing said latch arm from the normal restraining means

35 upon a predetermined amount of strand material being wound on the bobbins; the combination of a movable auxiliary restraining means also normally restraining said latch arm upon said latch arm being released from the normal restraining means, and means operable automatically

40 upon movement of the vertically reciprocatory frame in a predetermined direction for releasing the latch arm from the auxiliary restraining means to stop the machine.

5. In a strand processing machine such as a roving machine, slubber, speeder or the like having a vertically reciprocable frame, bobbins carried by said vertically reciprocable frame, a flyer associated with each of said

45 bobbins for directing strands to the bobbins, a stop motion, normal restraining means normally maintaining the stop motion in inactive position and means carried by the machine for automatically releasing said stop motion from the normal restraining means upon a predetermined amount of strand material being wound about the bobbins;

50 the combination of an auxiliary restraining means restraining said stop motion in running position upon said stop motion being released from the normal restraining means, and means operable automatically upon movement of the vertically reciprocable frame in a predetermined direction for releasing the stop motion from the auxiliary restraining means to stop the machine.

6. In a strand processing machine such as a roving machine, slubber, speeder or the like having a vertically reciprocable frame, bobbins carried by said vertically reciprocable frame, a flyer associated with each of said

65 bobbins for directing strands to the bobbins, a stop motion, normal restraining means normally maintaining the stop motion in inactive position and means carried by the machine for automatically releasing said stop motion from the normal restraining means upon a predetermined amount of strand material being wound about the bobbins;

70 the combination of an auxiliary restraining means restraining said stop motion in running position upon said stop motion being released from the normal restraining means, means operable automatically upon movement of the vertically reciprocable frame in a predetermined direction for releasing the stop motion from the auxiliary restraining means to stop the machine, and means controlling the releasing of the stop motion from the auxiliary restraining means to cause the bobbins to cease vertical movement at a predetermined position relative to the corresponding flyers.

75 7. In a strand processing machine having a vertically reciprocable frame, rotary bobbins carried by said frame, a flyer associated with each of said bobbins for directing strand material to the bobbins, a rock-shaft movable in

80 synchronism with said frame, a first stop motion in-

cluding an arm normally biased in one direction, normal means restraining movement of said arm and means operable automatically upon a predetermined amount of strand material being wound on the bobbins for releasing said arm from said normal means; the combination of an improved stop motion cooperating with said first stop motion and including an auxiliary restraining means, means on said arm engageable with said auxiliary restraining means, cam means movable with said rock-shaft, and means engageable with said cam means upon alternate movements of said rock-shaft to move said auxiliary restraining means away from said arm whereby, upon said arm being released from said normal means, said auxiliary means serves to restrain said arm until said cam means has subsequently moved said auxiliary means away from said arm to stop the machine.

8. In a yarn processing machine having a reciprocatory frame, rotary bobbins carried by said frame, a flyer associated with each bobbin for directing strand material to said bobbins, a rock-shaft movable in synchronism with said frame, a first stop-motion having an arm normally biased in one direction, normal means normally restraining movement of said arm in said direction and means operable automatically upon said bobbins being filled with strand material for releasing said arm from said normal means; the combination of a latch spaced above said rock-shaft and disposed above said arm, an abutment on said arm normally disposed adjacent said latch, a vertical shaft depending from said latch, a first

5 cam fixed on said rock-shaft, an eccentric auxiliary cam element eccentrically pivotally mounted on said first cam for movement about an axis parallel to said rock-shaft, and first and second laterally spaced stop means on said 10 first cam and being disposed adjacent opposite sides of the pivot point of said auxiliary cam element whereby said auxiliary cam element alternately engages each of said stop means as the pivot point thereof is alternately moved to opposite sides of its center of gravity, said auxiliary cam element being so formed that it will miss the lower end of said vertical shaft while in engagement with said first stop means, but will engage and elevate said vertical shaft while in engagement with the second stop means to move said latch out of engagement with said 15 abutment on said arm whereby, upon said arm first being released from said normal means, the auxiliary cam element, upon moving into engagement with said second stop means, will subsequently release said arm from the latch to permit the latch to be biased to machine- 20 stopping position.
